FUNNEL GUIDE BUSHING

Hugh D. Haley, Drexel Hill, Pa., assignor to American Viscose Corporation, Wilmington, Del., a corporation of Delaware

Application February 9, 1950, Serial No. 143,255

9 Claims. (Cl. 57—76)

1

This invention relates to funnel guides of the type used when spinning viscose rayon yarn into centrifugal pots, and more specifically to a mounting for such funnel guides.

Funnel guides of the type in prevalent use for spinning yarn comprise a glass funnel having a stem of approximately uniform outer diameter except for its end sections, and a lead ferrule supported concentrically on the stem near the bell-shaped or outwardly-flared upper section of the glass funnel. The ferrule is molded independently of the glass portion with an appreciably larger inside diameter than the outer diameter of the stem. The ferrule is affixed to the glass stem by supporting the ferrule and the glass funnel in a clamping fixture in the relationship desired in the finished spinning funnel and then by pouring molten sulphur into the annular space between the ferrule and the glass stem. When the molten sulphur solidifies, the spinning funnel may be removed from the fixture and attached to spinning equipment.

Funnel guides constructed in this manner have not been entirely satisfactory because of the cost resulting from the multiple-step procedure for producing them, and the considerable breakage which occurs when they are handled in quantity. The breakage may be attributed principally to their weight of which the lead ferrule is the major portion.

It is an object of the invention to provide a funnel guide of lighter and less expensive construction than the conventionally used guides having lead ferrules. It is still another object to provide a funnel guide having a stem portion replaceable within the ferrule. Another object is to provide a funnel guide less subject to breakage. Other objects, features and advantages will be apparent from the following description of the invention and the drawing relating thereto in which

Fig. 1 illustrates a funnel guide with portions in section;

Fig. 2 is an end view of a flexibly resilient bushing used in the funnel guide of Fig. 1; and

Fig. 3 illustrates in section a modified funnel guide.

In brief, the invention comprises a spinning funnel guide having its stem portion supported by spaced resilient bushings within a sleeve having interior circumferentially grooved surfaces, such as helically grooved inner surfaces, for receiving the outer surfaces of the bushings.

The drawing illustrates a funnel guide 4 supported by a bracket 5 in vertically and laterally adjustable relationship. Vertical adjustment of the guide relative to the bracket is obtained by turning the sleeve 1 of the guide within an interiorly threaded bushing 8 in threaded rela-

2

tionship with the sleeve. The adjustment may be fixed by tightening a lock nut 9. The bushing 8 extends through an aperture or slot of sufficient size in the bracket 5 to provide the clearances 11 and 12. The bushing is secured by gripping portions of the bracket surrounding the aperture between a flange 14 of the bushing and a lock nut 15 in threaded relationship with the bushing. A washer 17 of rubber-like resiliency is provided between the flange and the grooved or serrated surface 18 of the bracket. Lateral adjustment of the guide with respect to the bracket 5 is obtained within a range permitted by the clearances 11 and 12 by loosening the lock nut 15 and moving the bushing in any desired lateral direction and retightening the nut. The outer peripheries of the flange 14 and the nut 15 of the bushing and a flange 20 of the sleeve may be polygonal to receive a wrench or other tool. The sleeve has an inner cylindrical surface 2 in which is formed helical grooves 24 and 25 within the end portions of the sleeve.

A pair of bushings 26 and 27 each having a cylindrical outer surface such as that of bushings 28 illustrated in Fig. 2 occupy the end portions of the sleeve. The bushings preferably having a slightly greater diameter than that of the cylindrical surface 22 when removed from the bushing so that they will tightly occupy the ends of the sleeve and fill the helical grooves 24 and 25 when the stem 30 of the funnel extends through the bushings. The grooves 24 and 25 hold the bushings in place particularly when the stem 30 is forced through them such as when the guide is assembled or taken apart.

As funnel stems vary in diameter within an approximate range of $\frac{1}{2}$ of an inch, the bushings are preferably formed with diameters which cause them to fit tightly about the tubes of smallest diameter within the range of variation. Accordingly, these bushings may have a diameter equal to or slightly less than the smallest stem diameter anticipated. If desired, the bushings may be molded with a helical ridge which is complementary to the helical grooves 25 and 26. When the stem portion of the funnel is enlarged at both ends, a radially and longitudinally extending cut may be made in the wall of each bushing to implement its installation on the stem from a lateral direction.

The funnel guide may be assembled by pressing or screwing the bushings into place from opposite ends of the sleeve 1; the stem 30 of the funnel is thereafter pushed through the central apertures of the bushings. When the ends of the stem are enlarged, it will be necessary to first insert the funnel stem through the sleeve, then to place bushings having walls cut,

as hereinabove described, on the stem, and then, after lubricating the surfaces adequately, pressing or screwing the bushings into place. The outer surfaces of the bushings may be lubricated with water, oil or other lubricant to facilitate their movement into place within the sleeve. The outer surface of the stem or the inner surfaces of the bushing may also be lubricated when positioning the stem within the bushings. Removal of the stem may be facilitated by applying a lubricant at the outer surfaces of the stem adjacent the bushings and through a hole 32 into the annular space 33 surrounding the stem portion extending between the bushings.

The bushings 26 and 27 are fabricated from any resilient material which is resistant to the materials of the spin bath. Polyvinyl chloride, polyethylene, and polychlorobutadiene are examples of resins which have suitable resistance to the acid and the carbon disulfide ordinarily occurring in viscose rayon spinning baths. Such resins form satisfactory resilient bushings in which to mount the stem portion of a funnel guide. Soft, lightly vulcanized compositions containing natural rubber or synthetic rubbers which include polymerized butadiene are generally unsuitable for use in connection with the spinning of viscose rayon because of their rapid deterioration in the presence of carbon disulfide.

Since breakage from handling may be reduced to a large extent by reducing the weight of the funnel guide, the sleeve 7 is preferably constructed with as thin a wall as practical. The sleeve may be fabricated from any rigid material having the requisite molding and machining properties, and which is corrosion-resistant to materials of the spinning solution and the spinning bath. Of the metals, lead and alloys of lead and antimony are preferred when spinning viscose solutions. However, many plastic resins of suitable properties are available for molding a sleeve such as resins of phenol-furfural, methyl methacrylate, allyl, and vinylidene chloride; rubber compounds may be also used if vulcanized to a state of considerable hardness.

Fig. 3 illustrates a guide of which the sleeve 1a thereof has a smooth cylindrical or slightly tapered frustoconical surface 31. A guide of this type may be used in spinning installations wherein the guide must be quickly removed during the doffing operation by lifting it from its support. The sleeve 1a fits closely but not tightly within a sleeve 32 which by being in threaded relationship with the sleeve 14 may be rotated with respect to the latter sleeve to obtain vertical adjustment of the guide.

The use of the pair of spaced resilient bushings as a mounting for the guide is advantageous because of the positive alignment provided, the economical use of materials, the readiness with which the guide may be assembled or taken apart, and the ease with which parts of the guide may be lubricated to implement assembling or taking apart of the guide.

While preferred embodiments of the invention have been shown and described, it is to be understood that changes and variations may be made without departing from the spirit and scope of the invention as defined in the appended claims.

I claim:

1. A spinning funnel guide comprising a tubular stem portion, a pair of spaced bushings of flexibly resilient material extending tightly around the stem portion, and a rigid annular sleeve extending tightly around the bushings and

having circumferential grooves along each portion of its inner surface in contact with the bushings.

5 2. A spinning funnel guide comprising a tubular stem portion, a pair of spaced bushings of flexibly resilient material extending tightly around the stem portion, a rigid annular sleeve extending tightly around the bushings, said sleeve having helical grooves along each portion of its inner surface in contact with the bushings.

10 3. A guide as in claim 2 having bushings constituted of a composition which is essentially polyvinyl-chloride.

15 4. A guide as in claim 2 having bushings constituted of a composition which is essentially polyethylene.

20 5. A guide as in claim 2 having bushings constituted of a composition containing vulcanized polychlorobutadiene.

25 6. A spinning funnel guide in combination with mounting means therefor comprising a tubular stem portion, a pair of spaced bushings of a flexibly resilient material extending tightly around the stem portion, a rigid annular sleeve extending tightly around the bushings, said sleeve having helical grooves along each portion of its inner surface in contact with the bushings, mounting means having three dimensional adjustability in threaded relationship with the outer surface of the sleeve.

30 7. A spinning funnel guide in combination with mounting means comprising a tubular stem portion, a pair of spaced bushings of a flexibly resilient material extending tightly around the stem portion, a rigid sleeve extending tightly around the bushings, said sleeve having an outwardly extending flange at the end portion thereof nearest the strand receiving portion of the stem, mounting means for the funnel guide having a vertical aperture, said aperture complementarily contoured with respect to the outer surface of the sleeve.

35 8. A spinning funnel guide comprising a tubular stem portion, a pair of spaced bushings of a flexibly resilient material extending tightly around the stem portion, said bushings each having helical ridges extending around the outer surfaces, a rigid annular sleeve extending tightly around the bushings, said sleeve having helical grooves of complementary contour with the ridges of the bushings extending along each portion of its inner surface in contact with the bushings.

40 9. A spinning funnel guide comprising a tubular stem portion, a pair of spaced bushings of a flexibly resilient material extending tightly around the stem portion and having a slightly smaller inner diameter than the outer diameter of the stem when the bushings are removed from the stem, a rigid annular sleeve extending tightly around the bushings and the portions of the sleeve in contact with the bushings having a slightly smaller inside diameter than the outside diameter of the bushings when the sleeve is removed from the bushings, said sleeve having helical grooves along each portion of its inner surfaces in contact with the bushings.

Certificate of Correction

Patent No. 2,572,927

October 30, 1951

HUGH D. HALEY

It is hereby certified that error appears in the printed specification of the above numbered patent requiring correction as follows:

Column 2, line 21, for "surface 2" read *surface 22*; lines 25 and 26, for "bushings" read *bushing*; column 4, line 43, for "tubu-" read *tubular*;

and that the said Letters Patent should be read as corrected above, so that the same may conform to the record of the case in the Patent Office.

Signed and sealed this 19th day of February, A. D. 1952.
